UNITED STATES PATENT OFFICE.

JOHN W. ESKHOLME, OF WESTFIELD, NEW JERSEY, ASSIGNOR, BY MESNE ASSIGNMENTS, TO C. & C. ELECTRIC & MANUFACTURING COMPANY, A CORPORATION OF NEW JERSEY.

CIRCUIT-CONTROLLING APPARATUS.

1,122,488.

Specification of Letters Patent.

Patented Dec. 29, 1914.

Application filed September 23, 1909. Serial No. 519,160.

To all whom it may concern:

Be it known that I, JOHN W. ESKHOLME, a citizen of the United States, residing at Westfield, New Jersey, have invented certain new and useful Improvements in Circuit-Controlling Apparatus, of which the following is a clear, full, and exact description.

My invention relates to a circuit-controlling apparatus, particularly one for controlling the energizing circuit or circuits of an electric motor when it is desirable that said motor should have different speeds and work under variable loads, such as those operating printing presses and the like. There are various well known methods for controlling the speed of the motor such as introducing resistance in the main feeding circuit which is to be cut out and reinserted by a rheostat arrangement, or the more economic method of varying the strength of the field of the motor by various circuits.

It is immaterial in the present invention what method of speed control is employed since a feature of the present apparatus is a movable controlling member or arm adapted to make and break various connections. It is plain that these connections might be to different field circuits of the motor, or simply to different coils of resistance such as diagrammatically illustrated in the drawings Fig. 6.

The invention as illustrated further consists of the arrangement for operating this controlling arm by several push button circuits which give complete control over the motor at different parts of the machine. Push-button circuits are also provided for starting and stopping the motor, preferably by operating a main switch included in the motor energizing circuit, which switch may be of the general construction described in my Patent #780,164.

It is to be understood in the present specification and claims that references to the rheostat (shown in the drawings), such as cutting out and inserting resistance in the main circuit by the controlling member, is for the purpose of conventional description only and is not intended to limit the scope of the invention to the mere changing of resistance connections, since the changing of any connections whatever for controlling speed of the motor is contemplated.

The push-button circuits preferably comprise a starting circuit which acts to throw on the main switch, and thereafter by connections formed therefrom acts through the controlling member to cut out resistance of the main circuit and speed up the motor. The stopping circuit acts directly upon the electro-magnet of the main switch to operate the same for throwing the switch off. The slow-down circuit operating the controlling member acts to restore the resistance to the main circuit to slow down the motor. From each of the said named circuits I prefer to have several hand-operated switches or push-buttons and connections therefrom in order that a set of these push-buttons may be located at convenient places around the machine so as to be accessible to the operator at whatever portion of the machine he is engaged. In large machines like printing machines it is especially desirable that the machine be under the full control of the operator at several different parts of the machine, and this invention provides for such an arrangement. The starting and slow-down circuits as long as their push-buttons are depressed, act to operate the controlling member with a step by step movement and thus cut out and restore resistance to the circuit gradually. In starting the motor, however, I have provided an arrangement by which a single depression of the starting push-button will cause sufficient resistance to be gradually cut out of the circuit to start the motor, no matter how heavy its load, without the necessity of holding said push-button depressed or of closing the starting circuit a second time. Also when the machine has arrived at the desirable speed in the opinion of the head operator, it may be fixed at this speed by locking any one push-button of the starting circuit. The machine, however, may at all times be stopped by closing the stopping circuit and when any one of its switches is locked the machine cannot be started up without first unlocking that particular switch. Unless the starting switch or the stopping switch is locked, the slow-down button may be operated at any time to throw resistance in the main motor circuit, and thus slow down the speed of the machine. It will thus be observed that this arrangement provides for a perfect control at all times of the main

motor circuit from several different portions of the machine, or even from the foreman's office if so desired.

Other advantageous features of this apparatus, and of which the foregoing are among those of the illustrated form of the invention, will become clear in the particular description which follows.

My invention is shown in the preferred embodiment in the accompanying drawings, in which—

Figure 1 is an enlarged view of the rheostat mechanism having one of the actuating motors shown in section; Fig. 2 is an enlarged section through a single set of push-button switches; Fig. 3 is an enlarged section taken through Z—Z of Fig. 2 showing the locking means for one of the push-buttons; Fig. 4 is a detail section through Y—Y of Fig. 1; Fig. 5 is a section along X—X of Fig. 1; Fig. 6 is a diagrammatic view of the circuits and connections to the rheostat and main switch; and Fig. 7 is a partial view of the main switch.

Referring to Fig. 1 of the drawings, I will first describe my preferred form of controlling member and means for actuating the same. Mounted in any suitable way upon a back supporting plate 1 is a strip contact 52^b and a series of contacts 5, which, it is understood, may be connected to different field circuits or otherwise of the motor, but for the purpose of illustration are shown as connected to suitable resistance coils indicated at 58 in Fig. 6 and forming a rheostat. Loosely and rotatably mounted on a stud 4 extending outwardly from the plate 1 is a carrying wheel 2, and fixed at one side of this wheel is the controlling arm 3 which extends over the contacts 5 and strip 52^b to which the main circuit 52 is connected. The outer end of this arm 3 is preferably insulated from the main portion as shown in Fig. 1, so as to only bridge the contacts 5 and strip 52^b. I have diagrammatically indicated in Fig. 6 the main circuit 52 connected to the contacts 5 through arm 3, by means of a brush 52^a bearing on the hub of said arm 3. The right-hand end of the set of resistance coils is also connected to the main circuit 52, so that it is plain that this circuit is bridged through the resistance coils by means of said arm 3. Means for operating the controller arm 3 backward and forward over the contacts 5 consist preferably of two arms 6 and 7 independently mounted upon the outer end of stud 4 to oscillate freely thereon. Since these arms are similar in structure, a description of arm 6 will suffice for both. This arm 6 at its outer end is connected by means of any suitable universal connection 8 to a core 10 of a solenoid 18. The circuit 58^a for energizing this solenoid is broken below the same by means of separated contacts 22. These con-

tacts may be immersed in oil 21 contained in a receptacle 20 as is shown in Fig. 1 to prevent sparking. The lower end 19 of the core 10 is adapted to close the break between the contacts 22 when said core is in its lower position. It is clear that this arrangement is a self make-and-break device for the energizing circuit of the solenoid 18 which operates to give the core 10 a reciprocating motion as long as the remainder of circuit 58^a is closed. The energized solenoid draws the core upwardly which immediately breaks the circuit at 22 and thereby is allowed to fall by gravity to again close the same.

Carried on the outer end of the arm 6 is a bracket 12 containing within the same an inclined disk face 13. An unattached roller 14 lies within this bracket and is normally supported upon a stationary shelf 15 fixed to the back plate 1. A pin 16 extending through the upper end of the bracket 12 and surrounded by a downwardly pressing spring 17 bears upon the upper side of roller 14 to normally hold said roller down against its shelf 15. When the arm 6 is raised carrying the bracket 12, the inclined face 13 acts to bite or clamp the roller 14 against the rim of the wheel 2, and thereby carry the controlling arm 3 to the right a short distance, and when the arm 6 falls to its lower position as shown in Fig. 1, the roller 14 comes to rest upon the shelf 15 and no longer has a clamping action upon the rim of wheel 2, whereby said wheel is free to rotate. The arm 7 is operated by means of core 11 in precisely the same way to give the wheel 2 and controlling arm 3 a step by step motion in the opposite direction. Each reciprocation of core 10 or 11 may be adapted to move the arm 3 from one contact 5 to another. It is evident that when both of these arms 6 and 7 are in their lower position, the wheel 2 may be turned by hand if desired as the clamping devices are not active in this position. The two solenoids 18 and parts actuated thereby indicated as L and R in Fig. 6 constitute my electrically-operated actuating mechanism for the controlling member 3.

Referring to Fig. 7, the main switch 40 of the motor circuit is pivoted at 41 and carries integrally therewith a triangular plate 42. The electro-magnet or solenoid 44 is provided with the usual core 43 having a cross head 45 slidable thereon, said cross head being connected by means of slotted links 46 and 47 to opposite sides of the triangular plate 42. The upper end of the core 43 has fixed thereto a stud 49 which is adapted to engage the shoulders 48 at opposite sides of the triangular plate 42 to lock the same and switch 40 at either side of its throw. The cross head 45 loosely surrounds the core 43 and a coil spring 50 is disposed between the same and the stud 49 to nor-

mainly hold said core in an upward position. When the core 43 is drawn into its solenoid 44 the spring 50 is slightly compressed and stud 49 is unlocked from shoulder 46 and the 5 further travel of the core acts by means of the link 46 to throw plate 42 to the other side. The momentum of this plate 42 acts upon the other link and draws the cross head 45 upwardly again to its normal position, which in turn carries the core 43 up to lock the nose 49 behind the other shoulder 46, all as more particularly described in applicant's patent before referred to.

Referring to Fig. 2, the preferable form 15 of push-button switches as shown consist of a series of rods 25 extending into a closed case 23 and mounted on a suitable insulating plate 24. The lower end of these rods are immersed in a body of oil 32 contained in a receptacle 31 and have a portion 29 for bridging two separated contacts 30 which are fastened at the lower side of the insulating plate 24 as shown. At the upper end 20 of the rod 25 is a lug 27 for bridging two separated contacts 26 mounted at the upper side of the plate 24. The contact lug 27^a of the leftmost rod 25^a is of greater width than the other lugs, and also the lower end of said rod is provided with insulation as shown, 25 for a purpose to appear later. Springs 28 coiled between the lug 27 and plate 24 act to hold the rods 25 in an upward position, breaking the lower contacts 30 and closing the upper contacts 26. The two push-but- 30 tons 33^a and 33^b shown at the left in Fig. 2 which represent the starting and stopping push-buttons have a locking device, the preferred form of which is shown in section in Fig. 3. Said rod 25 in this figure is provided 35 with a sleeve having a slot at 34 on one side and a shoulder 35 at the other. A stud 36 passing through the casing and entering the slot 34 prevents the turning of the rod 25. Pivoted at 39 on the casing 23 is a latch de- 40 vice 37 having a ledge 38 and weighted at the side 37^a so as to have the tendency to tilt downwardly toward the left as shown in said figure. When the button 33^a and rod 25 are pushed down far enough, the ledge 45 38 will engage the shoulder 35 and hold the same in its lower position against the force of the spring 28. To unlock this push-button the latch 37 is thrown backwardly.

Referring now to Fig. 6, I will describe 55 the circuits and their connections which control the speed of the motor.

Motor circuit.—The main motor circuit consists of the line 52 from the positive main leading to the break 62 closed by a 60 contact plate of the main switch when on, and from here through the motor M to the contact 52^a across arm 3, through the resistance coils 58, thence to break 63, also closed by a contact of the main switch when 65 the same is on, and thence out to a negative

main. It will be observed that I have provided two breaks 62 and 63, one at each side of the main motor whereby no live circuit is connected to this motor when the switch is off.

Starting circuit and speed-up circuit.—The starting circuit 53 is led to the contacts 26^a of each of the starting switches in series which are bridged by the lugs 27^a thence is led to the contacts 30 at the lower end of starting switch, and thence to the separated contacts 26 and lugs 27 of the stop and slow-down switches of each set, to a contact 69 carried by and insulated from the arm 3, thence to the separated contacts 65 which are closed by the upper end of the main switch when off, and thence through the solenoid E and out to the negative main. Thus it is evident that the first depression of the push-button 33^b passes current 70 through this starting circuit to throw on the main switch 40, which immediately breaks said starting circuit at 65. A second or continued depression of the push-button 33^b, however, passes current through a speed-up 75 circuit which is traced as follows. A branch 53^a leads from the starting circuit 53 to the break 64 closed by the main switch 40 when on, thence to the solenoid L, thence to the end break 60 and out to the negative main. Subsequent depressions of button 33^b act to energize the solenoid L and give a step by step 80 movement to the arm 3 toward the right for cutting out resistance and thus speeding up the motor until said arm arrives at its extreme right-hand position where it separates the contact 60. The end break 60 is formed of any usual pivoted contacts normally held together by means of a spring. Also it will be noticed that unless the controlling 85 arm 3 is at its extreme left-hand or initial position, the circuit 53 will not be closed by contact 69, and therefore cannot energize the magnet E to throw on the switch. This arrangement in its illustrated application 90 prevents the switch from being thrown on, unless the entire resistance of the rheostat is in the main motor circuit 52.

Automatic circuit.—Located beneath the arm 3 are preferably placed two segmental contact strips 65^a and 66^a, and carried on the arm 3 insulated therefrom is a bridge 67 for completing a circuit through these contacts. The automatic circuit 57 is led first to a break 61 adapted to be closed when the 105 main switch is on, thence it is led to the contact run 65^a across the bridge 67 to 66^a, thence through solenoid L along line 53^a through the break 60, and out to the negative main. When the main switch is first 110 thrown on the circuit 57 is closed through 61 and immediately energizes the solenoid L to operate controller arm 3 step by step toward the right. This operation will take place until the bridge 67 travels past the 115

ends of 65^a and 66^a, and thus breaks the circuit. It will thus be understood that when the main switch is thrown on by means of the starting button, the automatic circuit 57 immediately acts independently to move the controlling arm a predetermined distance and gradually cut out resistance to a certain extent and slowly bring the motor into operation no matter how heavy its starting load may be. This arrangement has distinct advantages over controlling arrangements in which the resistance, even at the starting of the motor, is controlled entirely by a starting push-button, in which if the first depression of the button does not cut out sufficient resistance to start the motor under its load, it must be again depressed or held down until sufficient resistance is cut out to enable the motor to start.

The stopping circuit.—The stopping circuit 54 is led from the positive main through the contacts 30 of each stopping switch in parallel, thence to break 66 which is closed only when the main switch is on, and thence by means of line 53 through the solenoid E, out to the negative main. It will be noticed that this stopping circuit may be operated independently of any of the others at any time when the main switch 40 is on to close the break 66. Thus the motor may be stopped at any time that the main switch is on. This stopping circuit of course is broken and cannot energize electro-magnet E with the main switch located in its off position for this would operate to throw it on. As similarly the starting circuit cannot operate the electro-magnet E when the main switch is on.

Slow-down circuit.—The slow-down circuit 55 gets its connection to the positive main through lines 53, breaks 26^a, 27^a of the starting circuit. From 53 the slow-down circuit 55 leads in parallel to the contacts 30 of each slow-down push-button switch, and thence directly to the solenoid R around to the left-hand break 59, which is constructed similarly to that of 60, and out to the negative main. It will be understood whenever the slow-down push-button 33 is operated to close contacts 30, the motor solenoid R will be energized intermittently to move controlling arm 3 toward the left and restore resistance to the main circuit for slowing down the motor. The end break 59 is for the purpose of automatically breaking the circuit when arm 3 has reached its left-hand limit of travel.

As previously described, when either the stopping or slow-down push-button is operated the starting circuit 53 is broken through the contacts 26, and if the stopping switch is locked in its lower position the starting circuit is permanently broken through contacts 26 until the stopping switch is unlocked. Although the slow-down switch

when operated breaks the starting circuit through contacts 26, this slow-down circuit 55 itself still receives current through line 53 and is not broken through contacts 26^a of the starting switch even though said switch is depressed, for the reason that the lug 27^a of said starting switch is of greater width than the other lugs 27 and is designed to maintain the circuit through contacts 26^a even when the starting push-button is slightly depressed to close contacts 30. Thus it is plain that the slow-down circuit ordinarily has a preference over the starting circuit as it can be operated to slow down the motor no matter whether the starting switch is being depressed or not. However, arrangement is made by means of the starting switch and circuit to fix the speed of the motor at any desired position and prevent any change, except that of completely stopping the motor. The starting push-button is designed to be pressed downwardly a sufficient distance to carry its contact 29^a below the contacts 30 and also contact 27^a below contacts 26^a to break the same. The upper portion of contact 29^a is insulated to prevent current passing through the contacts 30 when in this lower position. The switch 33^b may also be locked in this lower position and thus maintain the starting circuit and the slow-down circuit broken through contacts 26^a, whereby no one of the slow-down or starting push-button switches can operate to speed up or slow down the motor without first unlocking this depressed and locked starting push-button.

An automatic restoring circuit 56 closed at its break 70 when the main switch is thrown off is led directly to the solenoid R through break 59 to the negative main, to energize said magnet R and move the arm 3 to its left-hand limit of travel at all times when the main switch is thrown off.

Another great advantage found in my arrangement of circuits is to be observed in regard to the slow-down circuit. This slow-down circuit in operating the arm 3 toward the left ceases to operate said arm after the bridge 67 has closed the break 65^a, 66^a, for the reason that at this point the automatic circuit 57 is immediately closed and the solenoid L is operating under its influence, as well as the solenoid R under the influence of the slow-down circuit. This results in bringing the arm 3 to a stop for the reason that the effect of the operation of both arms 6 and 7 simultaneously is that the wheel 2 is moved in neither one way nor the other. The purpose of this arrangement is that when the motor is operating under a heavy load, the torque of the motor cannot be sufficiently weakened either by changing the strength of the field of the motor or by inserting resistance in the main circuit through the operation of the slow-

down switch, to bring the motor to a complete stop with the main switch 40 still in its on position. Serious accidents would often occur without this arrangement for the reason that in the operation of a printing press, paper and other materials often clog the rollers, and if the torque of the motor were weakened to slow down, this clogging might be sufficient to stop the running of the machine entirely, and yet the energizing circuit of the operating motor would be closed through the main switch. In this condition while the operators think the machine is at a standstill the removal of the clogging material would suddenly lighten the load sufficiently to again start the machine without warning and perhaps injure the operators. It will be noticed also that the carrying wheel 2 and arm 3 have no fixed connection with the operating arms 6 and 7 and therefore may be turned by hand any time to operate the arm 3 independently of the controlling circuits.

As previously described, this invention comprehends the complete control over the starting, stopping and speed-up of a motor by means of push-button switches or independently by hand if desired, and it is of course understood that this invention is not limited to the particular devices for making and breaking the several circuits since these are only diagrammatically disclosed in many instances.

What I claim is:

1. In combination, a controlling member arranged to be moved forwardly and backwardly, electrically operated actuating mechanism for moving the same in either direction, such actuating mechanism comprising an electro-magnet armature or core and a switch, and of which there are a plurality of mechanically independent sets, a hand-operated switch operable at will for controlling one of said sets, and thereby said actuating mechanism in one direction, a separate hand-operated switch operable at will for controlling another of said sets, and thereby said actuating mechanism in the opposite direction, and means for imparting a continuous step by step movement through the medium of said actuating mechanism to said controlling member when one or the other of said hand-operated switches is closed.

2. In combination, a controlling member arranged to be moved gradually in a forward and backward direction, electrically-operated-actuating mechanism for moving the same, energizing circuits for said actuating mechanism, including said switch, a hand-operated switch operable at will for controlling said actuating-mechanism in one direction, and a separate hand-operated switch operable at will for controlling said actuating mechanism in the opposite direc-

tion, a cut-out switch automatically operated by said controlling member at each end of its travel and adapted to break the energizing circuits of said actuating mechanism, a third hand-operated switch, and means controlled thereby for automatically opening or closing said energizing circuits independently of said cut-out switch.

3. In combination, a controlling member arranged to be moved step by step, an electro-magnet for moving the same, an energizing circuit therefor, a hand-operated switch adapted to close said circuit, means for holding said switch closed, an automatically operated switch in said circuit adapted to break and make said magnet circuit at each energization of said magnet, a slow-down switch, and means to prevent the slowing down of the motor while the said hand-operated switch is acted on by said means for holding it closed.

4. In combination, a controlling member, power transmitting means, corresponding devices moved back and forth but one at a time by the application of said power, and friction means for each of said devices adapted to give said controlling member a step by step movement in either of two directions when repeated back and forth movements are given to one or the other of said devices, said controlling member being free from fixed connection to said friction means, whereby the said controlling member may be independently moved by hand at will in said two directions.

5. In combination, a controlling member movable in either of two directions, manually governed power transmitting means, mechanically separate corresponding reciprocating devices moved one at a time by the application of said power, and means for repeatedly connecting one or the other of said devices to said controlling member for imparting a positive step by step movement thereto in one or the other of said two directions during the movements of said repeatedly connected device in one direction, whereby said controlling member receives a movement at will in either of two directions.

6. In combination, a controlling member, power transmitting means, reciprocating devices moved by the application of said power, a wheel fixed to said controlling member and friction connecting means carried by said reciprocating devices adapted to clamp said wheel during the movement of said devices in one direction whereby said controlling member receives a step by step movement, said friction devices permitting a free movement of said wheel in either direction independently thereof.

7. In a circuit controlling apparatus in combination, a main circuit and a main switch therefor, a rheostat included in said main circuit, an electrically-operated-actu-

ating mechanism for operating said rheostat to vary the resistance of said main circuit, a circuit closed when said main switch is on adapted to energize said actuating mechanism, and means energized by said second circuit to cut out, in a step by step manner, a portion of the resistance of said rheostat from said main circuit.

8. In a circuit-controlling apparatus in combination, a main circuit and a main switch therefor, a rheostat included in said main circuit, electrically-operated-actuating mechanism for operating said rheostat, a circuit closed when said main switch is on adapted to energize said actuating mechanism, and means energized by said second circuit to cut out, in a step by step manner, a portion of the resistance of said rheostat from said main circuit, and a separate circuit controlled by a hand-operated switch for energizing said actuating mechanism to further cut out resistance of said rheostat.

9. In a circuit-controlling apparatus in combination, a main circuit and a main switch therefor, an electro-magnet for operating said switch, electrically-operated-actuating mechanism operable to vary the resistance in said main circuit, a hand-operated starting switch and circuits controlled thereby adapted to energize said electro-magnet when said main switch is off and to energize said actuating mechanism when said main switch is on, said electro-magnet being energized by circuits independent of the motor circuit.

10. In a circuit controlling apparatus in combination, a main circuit and a main switch therefor, a rheostat included in said main circuit, electrically-operated-actuating mechanism for operating said rheostat, a hand-operated switch and a circuit controlled thereby for energizing said actuating mechanism to throw resistance in said main circuit, and means to prevent the entire resistance of said rheostat being thrown into said circuit by the operation of said hand switch when the main switch is on.

11. In a circuit-controlling apparatus in combination, a main circuit and a main switch therefor, a rheostat included in said main circuit, electrically-operated-actuating mechanism for operating said rheostat, a hand-operated switch and a circuit controlled thereby for energizing said actuating mechanism to throw resistance in said main circuit, and means to prevent the entire resistance of said rheostat being thrown into said circuit by the operation of said hand switch when the main switch is on, and automatic means for throwing the entire resistance of said rheostat in said circuit when said main switch is off.

12. In a circuit-controlling apparatus in combination, a main circuit and a main switch therefor, a rheostat included in said

main circuit for varying the resistance therein, means for operating said switch and rheostat, and a series of circuits for controlling said operating means comprising a starting circuit for throwing on said main switch, an automatic circuit closed by said main switch, an automatic circuit closed by said main switch for cutting out a predetermined amount of resistance from said main circuit, and a speed-up circuit for further cutting out resistance from said main circuit to speed up the motor.

13. In a circuit-controlling apparatus in combination, a main circuit and a main switch therefor, a rheostat included in said main circuit for varying the resistance therein, means for operating said switch and said rheostat, and a series of circuits for controlling said operating means comprising a starting circuit for throwing on said main switch, a speed-up circuit for cutting out resistance from said main circuit, a slow down circuit for restoring the resistance to said main circuit, and a stopping circuit for throwing off said main switch, a restoring circuit closed when said main switch is off for restoring the resistance of said rheostat to said main circuit.

14. In a circuit-controlling apparatus in combination, a motor and a main energizing circuit therefor, a main switch for said motor circuit, a movable controlling member for varying the speed of said motor, electrically-operated-actuating mechanism for operating said controlling member, an energizing circuit for said actuating mechanism closed by said main switch when on and adapted to move said controlling member a predetermined distance for starting the motor.

15. In a circuit-controlling apparatus in combination, a motor and a main energizing circuit therefor, a main switch for said motor circuit, a movable controlling member for varying the speed of said motor, electrically-operated-actuating mechanism for operating said controlling member, an energizing circuit for said electro-actuating mechanism closed by said main switch when on and adapted to move said controlling member a predetermined distance for starting the motor, a separate energizing circuit for said actuating mechanism closed by a hand-operated switch and adapted to further move said controlling member for speeding up said motor.

16. In a circuit-controlling apparatus in combination, a motor and a main energizing circuit therefor, a main switch for said motor circuit, a movable controlling member for varying the speed of said motor, electrically-operated actuating mechanism for operating said controlling member, an energizing circuit for said electro actuating mechanism closed by a hand-operated switch

adapted to move said controlling member for speeding up said motor, a separate energizing circuit for said actuating mechanism closed by said main switch when off adapted to restore said controlling member to its initial position.

17. In a circuit controlling apparatus in combination, a motor and a movable controlling member for varying the speed of said motor, electrically operated actuating mechanism for operating said controlling member, each such actuating mechanism including an electro-magnet armature or core and a switch, a plurality of independently controllable hand-operated switches, independent circuits for energizing said actuating mechanism, including said first switches, and each separately controllable at will by one of said hand-operated switches and adapted to move said controlling member in different directions for speeding up and slowing down said motor, and means for imparting a continued step by step movement through the medium of said actuating mechanism to said controlling member when one or the other of said hand operated switches is closed, said independent circuits being independent of control by the motor circuit.

18. In a circuit-controlling apparatus in combination, a motor and a main energizing circuit therefor, a main switch for said motor circuit, a movable controlling member for varying the speed of said motor, electrically-operated-actuating mechanism for operating said controlling member, independent circuits for energizing said actuating mechanism each separately controlled by a hand-operated switch and adapted to move said controlling member in different directions for speeding up and slowing down said motor, and means to prevent said controlling member from being restored to its initial position while said main switch is on.

19. In a circuit controlling apparatus in combination, a motor and a main energizing circuit therefor, a main switch for said motor circuit, an electro-magnet for operating the same, a movable controlling member for varying the speed of said motor, an energizing circuit for operating said electro-magnet to throw on said main switch closed by a hand-operated switch and adapted to be broken when said controlling member is away from initial position.

20. In a circuit-controlling apparatus in combination, a motor and a main energizing circuit therefor, a main switch for said motor circuit, an electro-magnet for operating the same, a movable controlling member for varying the speed of said motor, and means to prevent the actuation of said electro-magnet to throw on said main switch when said controlling member is away from initial position.

21. The combination with a motor, of a series of electrical circuits for controlling the operation and speed of said motor, comprising a starting circuit, a speed-up circuit, a slow-down circuit and a stopping circuit, one or more of hand-operated switches for each of said circuits, said starting and speed-up circuits being closed by the same switch or switches and also bridged through the switches of said stopping and slow-down circuits whereby they are broken when one of said latter switches is closed.

22. The combination with a motor, of a series of electrical circuits for controlling the speed of said motor, comprising a speed-up circuit, and a slow-down circuit, one or more hand-operated switches and connections for closing each of said circuits, means operated by any one switch of the speed-up circuit to break the connections of the other switches of said circuit and also the connections for said slow-down switch or switches.

23. The combination with a motor, of a series of electrical circuits for controlling the speed of said motor, comprising a speed-up circuit and a slow-down circuit, one or more hand-operated switches and connections for closing each of said circuits, means for locking any one speed-up switch in position to break the connections for the other switches of said circuit and also the connections for said slow-down switch or switches whereby the speed of said motor may be fixed.

24. The combination with a motor, of a series of electrical circuits for controlling the operation of said motor comprising a starting circuit and a stopping circuit, one or more hand-operated switches and connections for each of said circuits, means for locking a switch of the stopping circuit to break the connections for the starting switch or switches and maintain said starting circuit broken, a switch of said starting circuit being biased to a closed position when said locking means is unlocked.

25. The combination with a motor, of a series of electrical circuits for controlling the operation and speed of said motor, comprising a starting circuit, a speed-up circuit and a stopping circuit, one or more hand-operated switches and connections for each of said circuits, said starting and speed-up circuits being closed by the same set of switch or switches and also bridged through the switch or switches of said stopping circuit whereby they are broken when one of said latter switches is closed.

26. The combination with a motor, of a series of electrical circuits for controlling the speed of said motor, comprising a speed-up circuit and a slow-down circuit, one or more hand-operated switches for each of

said circuits, the switch or switches of said slow-down circuit being biased to a closed position, said speed-up circuit being bridged through the switch or switches of said slow-down circuit and adapted to be broken when one of the same is operated.

Signed at Garwood N. J. this 21st day of Sept. 1909.

JOHN W. ESKHOLME.
